UNITED STATES PATENT OFFICE.

ALBERT T. FISCHER, OF CLEVELAND, OHIO.

DESIGN FOR A CLOCK-CASE.

No. 37,852.

Specification for Design.

Patented Feb. 27, 1906.

Application filed January 8, 1906. Serial No. 295,190. Term of patent 7 years.

To all whom it may concern.

Be it known that I, ALBERT T. FISCHER, a citizen of the United States, residing at Cleveland, in the county of Cuyahoga and State of Ohio, have invented a new and original Design for a Clock-Case, reference being had to the accompanying drawing, the figure of which is a perspective view showing the design of the clock-case.

I claim—

The ornamental design for a clock-case, as shown.

ALBERT T. FISCHER.
